8-23

No. 13,430

Nov 14, 1882

UNITED STATES PATENT OFFICE.

JOHN L. POPE, OF CLEVELAND, OHIO.

DESIGN FOR A CARRIAGE-WRENCH.

SPECIFICATION forming part of Design No. 13,430, dated November 14, 1882.

Application filed August 2, 1882. Term of patent 14 years.

To all whom it may concern:

Be it known that I, JOHN L. POPE, of Cleveland, in the county of Cuyahoga and State of Ohio, have invented and produced a new and original Design for Carriage-Wrenches, of which the following is a specification, reference being had to the accompanying engraving, forming part thereof.

My invention relates to a design for carriage-wrenches; and it consists in certain features of ornamentation, which will be fully described farther on, and specifically pointed out in the claims of this specification.

As will be seen, the wrench illustrated in the accompanying engraving is of about the usual form or structural shape—that is, the shank is provided at one end with a square jaw for engaging the axle nut or bolt and at the other end with a three-sided jaw or opening for catching upon other smaller nuts or bolts that may be used in the construction of the carriage or other vehicle, all as fully understood by those who have occasion to use these devices. I have improved the appearance of this wrench by forming a raised portion, rib, or bead all along the two upper edges of the shank or handle and all along the curved widened part of the wrench, at which is lo-

cated the before-mentioned three-sided jaw. This bead or raised portion will be found indicated in the engraving by the letter *a*. I have further ornamented the wrench by forming a "swell" or convexity, *b*, along the handle between the ribs *a a*, which convex portion, it will be seen, gradually becomes thinner as it approaches the three-sided jaw part of the wrench and vanishes at about the point *X*.

What I claim as of my invention, and desire to secure by Design Letters Patent, is—

1. A carriage-wrench having beaded edges *a*, substantially as shown and described.
2. A carriage-wrench having the central swell, *b*, substantially as shown and described.
3. A carriage-wrench having the central swell, *b*, made to disappear as it enters the widened three-sided jaw part of the wrench, substantially as shown and described.
4. A carriage-wrench having beaded edges and a central swell along the shank, substantially as shown and described.

In witness whereof I have hereunto set my hand this 17th day of July, 1882.

JOHN L. POPE.

In presence of—

L. S. FISH,

FRANK N. WILCOX.
